UNITED STATES PATENT OFFICE.

DAVID T. BARNETT, OF CINCINNATI, OHIO.

SAND-VALVE MECHANISM.

No. 896,968.

Specification of Letters Patent.

Patented Aug. 25, 1908.

Application filed February 24, 1908. Serial No. 417,361.

To all whom it may concern:

Be it known that I, DAVID T. BARNETT, a citizen of the United States, residing at Cincinnati, in the county of Hamilton and State 5 of Ohio, have invented new and useful Improvements in Sand-Valve Mechanisms, of which the following is a specification.

This invention relates to new and useful improvements in sand valve mechanisms, 10 which may be applied to any conveyance or motor vehicle traveling upon track rails, such as locomotive steam engines. Heretofore these devices have generally been placed in the sand bin, and hence have been subject to 15 frequent clogging and in such devices their operation has been impaired, due to the fact that some of the sand's weight had to be acted against before the sand valve could be opened. They had no alternative means of 20 operation, and if the means designed to operate them failed, the sand valve mechanism was out of commission.

The object of this invention is to provide a sand valve mechanism which may be placed 25 wholly without the sand bin, in the line of the pipe leading from the bin to the tracks; is ordinarily operated by a fluid under pressure and when the fluid pressure is cut off purposely or accidentally, is capable of being 30 operated by other means. Furthermore to provide such mechanism that no part of the weight of the sand will be acted against by the operation of the device; and to construct the entire device in such a manner as not to 35 tend to stop the flow of sand in the pipe.

The particular embodiment of my invention selected for illustration, is designed for use on a locomotive steam engine.

Figure 1 is a full section of the entire device, taken axially. Fig. 2 is a plan view of 40 one of the spiders which aid in supporting the operating mechanism. Fig. 3 is a plan view of a detail of the hand operated mechanism, viz: the yoke, the levers pivoted to 45 it, and a connecting link.

Referring to the drawings, A, A¹ is the main casing bolted together through lugs a¹⁰ by bolts a. Both parts of the casing A and A¹ have threads a¹ and a² at their extremities to receive the threaded portions of the 50 pipes or their unions leading from the sand bin to the track. The sand enters the opening a³ and passes out the opening a⁴.

The lower part of the casing A embraces 55 near its bottom a conical shaped interior surface a⁵ whose lower portion serves as a

seat for valve b³ and has a circular opening a¹¹. Valve b² is threaded to rod b, which may or may not be integral with a piston B, which operates in cylinder C. Said piston B 60 has a sliding fluid tight fit in said cylinder, made by the ordinary piston rings b⁷ or their equivalent. Threaded to a central projection on the bottom of cylinder C is valve guide c, which is pierced by rod b and has a 65 countersunk recess in which valve b² operates and is guided. Valve b² and the guide are so formed as to make the least possible resistance to the sand in the surrounding conical space of the shell and exclude the same from 70 the space in the guide c. Packing box c¹ permits a fluid tight fit between piston rod b, the projection on the bottom of cylinder C and valve guide c. An inlet a⁶ in casing member A connects with the actuating fluid 75 reservoir, and is connected to the inlet c³ at the bottom of cylinder C by a tube threaded in inlets a⁶ and c³. If the mechanism is adjusted correctly, the bottom of the piston B is flush with or above the top of inlet c³ when 80 the valve is seated.

The head c² of cylinder C is pierced by piston rod b¹ and affords an annular space for the operation of spring b⁴, which is confined between the head and piston and constantly 85 produces downward pressure on the piston B; said pressure being transmitted through rod b and valve b² to the valve seat.

Cylinder head c², cap D and the cylinder C are held together by bolts d, extending 90 through lugs c⁵, c⁶, and d². Cap D has a conical or other suitably shaped top, the purpose of which is to divert the sand into the openings of the spiders. The sides and top of the cap D and the top of the cylinder head c² 95 form a chamber into which piston rod b¹ extends from the cylinder proper. At the end of said rod b¹ is a nut b⁵, either fastened to or integral with the same. Just below said nut b⁵ is a plate b⁶ fixed to rod b¹ and contacting 100 with levers e pivoted to plate b⁶ by means of pin e¹ which pierces and operates in a lug integral with or fastened to the plate, said lug shown in a dotted line in the drawing. Lever e is also pivoted to a slotted part or yoke e², 105 which is slidably pierced by rod b¹.

Aperture a⁷ in the casing A is connected to aperture d¹ in the cap D by means of a threaded tube e³. Link E, which may or may not connect to any system of levers, is 110 longitudinally adjustable within tube e³, is threaded in the slotted part or yoke e², and

provides for operation of the valve without fluid pressure, and entirely independent of the piston. Notches a^8 and a^9 in the casing A and A¹ and notches c^4 and d^3 in the central mechanism receive spiders F and F¹ respectively, which holds said central mechanism rigidly in position.

A suitably limited opening b^3 in piston rod b and valve b^2 , shown dotted, may or may not be provided with a plug at the outlet a^4 . Its purpose is to allow part of the actuating fluid to pass out of outlet a^4 and entrain the sand with it. However, there would be no need for such provision, as the force of gravity would be sufficient, unless the pipe leading from the sand valve mechanism to the track was badly arranged or contained some acute bends.

The operation of the device is as follows:— When the valve b^2 is desired to be unseated and sand allowed to be scattered over the track, air under pressure or a fluid of like properties is admitted to the aperture a^6 by means of a valve in the pipe line between the fluid reservoir and said aperture, (said valve and pipe line not shown in the drawings). The fluid then passes through a tube, which connects aperture a^6 and c^3 ; into aperture c^3 and raises piston B acting against the force afforded by spring b^4 , said piston carrying with it rod b and valve b^2 , and unseating the same. Said valve sheaths in the counter bore of the valve guide c. Sand is now free to flow, due to the action of gravity, out of aperture a^{11} through the pipe to the track, said pipe or its union being threaded in threads a^2 . If a by-pass b^3 is embraced by the rod b and valve b^2 part of the fluid passes through it and out aperture a^4 to the track, entraining the sand. To stop the flow of the sand, the fluid is prevented from entering aperture a^6 by closing the valve in the pipe line between the fluid reservoir and aperture a^6 . When this is accomplished, there is no pressure on the under side of piston B and spring b^4 free to act, exerts pressure on the top of the piston, which forces the same downward. This motion is transmitted through rod b to the valve b^2 which is seated, and held firmly on its seat, due to the pressure exerted on the piston by the spring. The fluid which is left in the pipe to the reservoir, between the auxiliary valve and the device, also that fluid which is in the device itself, flows through conduit b^3 and clears the pipe after its auxiliary valve is closed. However, if the actuating fluid should fail to raise the piston, due to some parts sticking, or if it is desired to operate the valve when the air is cut off, the piston could be raised by pulling outward on link E which would slide the slotted part or yoke e^2 to which it connects. This movement of link E would cause lever e, which is pivoted to plate b^6 and yoke e^2 to assume a more vertical position and raise

plate b^6 , which would in turn raise the valve against the force of spring b^4 , the motion of plate b^6 being transmitted to nut b^5 , then through rod b^1 , piston B and rod b to the valve proper.

It is obvious that any system of levers could be connected to link E, such as would give the desired motion to said link. Also it is obvious that the mechanisms operating the valve, namely the ones operating it by hand and by means of the fluid, operate absolutely independently of one another.

What I claim as my invention and desire to secure by Letters Patent of the United States, is:—

1. A sand valve device embodying in combination a sand discharging conduit, a valve for controlling same, means for operating the valve normally by fluid pressure, and auxiliary means for operating same positively by hand for emergency purposes.

2. A sand controlling and discharging device embodying in combination (1) a casing constituting an integral part of the discharge conduit enlarged, (2) a lift valve controlling the lower orifice of the casing, (3) a smaller casing arranged concentrically within the first, (4) a valve stem extended axially within the inner casing, and, (5) manually operated mechanism contained wholly within the inner casing for operating the valve.

3. In a device of the character described, having an outer and inner casing concentrically arranged and a valve controlling the lower orifice of the former with stem extended axially into the latter, a countersunk boss attached to the lower end of the inner casing embracing the valve and constituting a guide, socket and sand shield for the same.

4. A sand valve mechanism, having in combination a casing with an opening at the top to connect with the sand supply and another at the bottom for a sand exit, another casing within the first and free therefrom save by connections between the sides of both said casings, a valve controlled from said inner casing adapted to close the sand exit opening in the outer casing and a lever mechanism within the second-named casing for causing the vertical reciprocation of said valve.

5. A sand valve mechanism, having in combination a casing constituting an enlargement of the feed pipe, with an opening at the top to connect with the sand supply and another at the bottom for a sand exit, another casing within the first and free therefrom save by connections between the sides of both said casings, a valve controlled from said inner casing adapted to open the sand exit opening in the outer casing, both by fluid pressure and by positive mechanical means.

6. A sand valve mechanism, having in combination a casing with an opening at the top to connect with the sand supply and an

other at the bottom for a sand exit, another casing within the first and free therefrom save as to connections between the sides of both said casings, a valve controlled from 5 said inner casing adapted to open the sand exit opening in the outer casing by the action of fluid under pressure, and a guide for the valve into which said valve recedes when it is moved to uncover the sand exit.

10 7. A sand valve mechanism, having in combination a casing, constituting an enlargement of the feed pipe with an opening at the top to connect with the sand supply and another at the bottom for a sand exit; 15 another casing within the first and free therefrom save by connections between the sides of both said casings, a valve controlled from

said inner casing normally adapted to keep closed the sand exit opening in the outer casing and means for admitting fluid under pressure to raise the valve and means to afford the escape of a portion of said fluid through the sand exit to entrain the sand. 20

8. In combination with a sand valve mechanism, a valve guide threaded to a projection of the bottom of the cylinder and having a counterbore adapted to receive the valve. 25

In testimony whereof I have hereunto set my hand in presence of two subscribing witnesses.
